UNITED STATES PATENT OFFICE.

LUDWIG MOND, OF LONDON, ENGLAND.

APPARATUS FOR OBTAINING ZINC BY ELECTROLYSIS.

SPECIFICATION forming part of Letters Patent No. 701,216, dated May 27, 1902.

Application filed March 4, 1902. Serial No. 96,691. (No model.)

To all whom it may concern:

Be it known that I, LUDWIG MOND, a citizen of England, residing at 20 Avenue road, Regents Park, London, England, have invented certain new and useful Improvements in Apparatus for Obtaining Zinc by Electrolysis, (for which I have applied for a patent in Great Britain, dated March 19, 1901, No. 5,764; in Spain, dated December 24, 1901; in Germany, dated August 8, 1901, and November 27, 1901; in France, dated December 13, 1901; in Belgium, dated December 14, 1901; in Italy, dated December 18, 1901; and obtained a patent in Canada, dated November 12, 1901, No. 73,705,) of which the following is a specification.

For depositing zinc from its solutions, and more particularly from alkaline solutions, by electrolysis a great difficulty has been found in obtaining the metal in a coherent form. It is usually obtained in the form of a spongy mass, which oxidizes so readily on being withdrawn from the electrolytic bath that on attempting to melt it only a small percentage of the zinc originally deposited is obtained as metal, the bulk presenting itself as oxid. Various means have been proposed to overcome this difficulty, such as depositing the zinc upon revolving cathodes in the form of disks or cylinders which are partly immersed in the electrolyte. With great precautions a coherent metallic deposit of zinc can be obtained in this way up to a certain thickness, rarely exceeding, however, one-eighth of an inch, after which the deposit becomes spongy. According to my present invention, which was originally included in my application filed August 12, 1901, Serial No. 71,775, I entirely overcome this difficulty and obtain coherent metallic deposits of any thickness by employing apparatus by which the metal is subjected to a constant rubbing action under pressure while it is being deposited. For this purpose I make the cathodes upon which the zinc is to be deposited cylinders of conducting material and arrange several of them in a row, each touching the next, in one electrolytic bath. These cylinders are provided with shafts moving in bearings which are mounted so that they can slide, and I apply pressure upon all or several of these cylinders by means of weights, springs, levers, or other mechanical device, which presses the

cylinders against each other and at the same time allows them to move farther apart as the thickness of the zinc deposited upon them increases. All the cylinders may be rotated separately by any convenient motor; but I prefer to drive only some of them, the others being rotated by frictional contact. The said apparatus can be constructed in variously-modified ways for carrying out my invention, as I will describe with reference to the accompanying drawings.

Figure 1 is a part-longitudinal section of an arrangement of the apparatus with the cathode-cylinders arranged in a horizontal row. Fig. 2 is a part plan. Figs. 3 and 4 are respectively an enlarged cross-section and a front view of one of the bearings of the shaft of cylinder *a*. Fig. 5 is a longitudinal section of an arrangement in which the cathode-cylinders are superposed, Fig. 6 being a section on the line 8 8 of Fig. 5 and Fig. 7 a sectional plan and Fig. 8 an enlarged detail of this construction.

Referring to Figs. 1 and 2, the cylinders *a* and *b b'* have their shafts mounted in bearings *c* and *d d'*, pressed against each other by springs *e* or their equivalents. All the cylinders may be rotated by any convenient motor; but I prefer to drive only one of them, *b*, as by a belt *f* on pulley *g*, as shown, the others, *a b'*, being rotated by frictional contact. I make these cylinders of slightly-different diameters, a smaller between each two larger, so that the same points on their circumferences do not come in contact until after many revolutions. I also give alternate cylinders *a* besides rotation a to-and-fro longitudinal motion for producing the above-described rubbing action and also to avoid the formation of grooves in the deposited metal. This to-and-fro motion, which need not exceed an inch, may be obtained, as shown, by cutting an inclined groove in one of the bearings and mounting on the shaft, which works in it, a roller *h*, fitting loosely in this groove. The bearings of the cylinder-shafts are insulated and connected to the negative terminal of a source of electricity, or, as shown in Fig. 2, each of the cylinder-shafts has on its end a metallic disk *l*, dipping into mercury in an insulated cup *m*, all of which cups are connected to the negative pole of the source of

electricity. The other pole is connected to the amalgam p , which occupies the lower part of the cell. This amalgam is obtained in the known manner by the electrolysis of sodium 5 or potassium chlorid with a mercury cathode, and when it is employed as anode it should be kept constantly flowing over the bottom of the cell. When such amalgam is not available, anodes may be employed of carbon or 10 of platinum, iron, or other metals that are not oxidized by electrolytic oxygen in alkaline solution. In order to facilitate the removal of the deposited zinc, the cylinders should be coated with a little graphite or 15 paraffin or any other suitable substance which prevents contact of the deposited zinc with the metal of the cylinder.

In the modification shown in Figs. 5, 6, and 7 the cylindrical cathodes $a b b$ are superposed. In this case the cylinders are pressed 20 against each other by weights $r r$, which are mounted on the shaft of the top roller b and are of sufficient weight to counteract the buoyancy of the cylinders in the electrolyte. The 25 middle cylinder a receives a slight longitudinal to-and-fro motion and is of diameter slightly different from that of the other cylinders. The cathode-cylinders $a b b$ may be made hollow, as shown, the cylindrical part 30 of each being insulated from the two ends by rings o of insulating material, such as ebonite. The bearings $c c'$ and d for the axes of the cylinders are fitted to slide in vertical guides n , the bearing c and the axis which 35 works in it being arranged as described with reference to Figs. 3 and 4. $p' p'$ are the anode-plates, which are preferably corrugated, as shown in Fig. 6, so as to have all their parts approximately equidistant from the 40 surfaces of the cylinders. The cylinders $a b b$ are connected to the circuit by a contact-spring brush m , applied to the top roller. The cathode-cylinders being hollow, a suitable packing has to be provided to prevent 45 the electrolyte from penetrating into them at the center. This may conveniently be effected as shown at Fig. 8, where a caoutchouc or ebonite ring s is compressed in the recess of the boss, so as to form a water-tight joint 50 by means of a steel washer t and screw-nut u .

Having thus described the nature of this invention and the best means I know of carrying the same into practical effect, I claim—

1. In apparatus for obtaining zinc by electrolysis, the combination of a number of cylindrical cathodes rotating in contact with

each other within an electrolytic bath, means for pressing the cylinders against each other and means for producing a longitudinal rubbing action between the cylinders, substantially as described. 60

2. In apparatus for obtaining zinc by electrolysis, the combination of a number of cylindrical cathodes rotating in contact with each other within an electrolytic bath every 65 alternate cylinder being of diameter different from that of the others, means for pressing the cylinders against each other and means for producing a longitudinal rubbing action between the cylinders, substantially as described. 70

3. In apparatus for obtaining zinc by electrolysis, the combination of a number of cylindrical cathodes rotating in contact with each other within an electrolytic bath, means 75 for pressing the cylinders against each other, means for driving the one cylinder by external power which cylinder gives rotation to the others by frictional contact, and means for producing a longitudinal rubbing action 80 between the cylinders, substantially as described.

4. In apparatus for obtaining zinc by electrolysis, the combination of a number of cylindrical cathodes rotating in contact with 85 each other within an electrolytic bath, means for pressing the cylinders against each other and means for imparting a longitudinal to-and-fro motion to some or all of the cylinders for producing a rubbing action between them, 90 substantially as described.

5. In apparatus for obtaining zinc by electrolysis, the combination in an electrolytic bath of a number of rotating horizontal cylindrical cathodes each differing somewhat in 95 diameter from that or those next to it, pressed toward each other by means which allow their axes to move farther apart, all these axes being mounted in sliding bearings, and one of the axes of each alternate cathode being provided with a stud engaged in an inclined groove in its bearing, so that as such cathode revolves, it is moved to and fro longitudinally, 100 substantially as and for the purpose set forth.

In testimony whereof I have hereunto set 105 my hand in presence of two subscribing witnesses.

LUDWIG MOND.
